UNITED STATES PATENT OFFICE

2,517,950

DISK SHARPENER

Raymond H. Weirich, Toledo, Ohio.

Application June 13, 1946, Serial No. 676,387

4 Claims. (Cl. 51—106)

1

This invention relates to a device for grinding circular blades and particularly the gang of disc blades on harrows or the like.

An object of this invention is to produce a new and improved grinder for sharpening one or more disc blades without their previous disengagement from the mounted position.

Another object of this invention is to produce a disc blade sharpener consisting of relatively few simple parts readily assembled to provide a sturdy portable grinder adapted uniformly to sharpen discs while in the mounted position.

A further object is to produce a disc blade sharpener having individual power means separately to drive the disc blades and the grinding wheel and adapted simultaneously and uniformly to sharpen one or more disc blades.

These and other objects will hereinafter appear and for purposes of illustration, but not of limitation, embodiments of the invention are shown in the accompanying drawings in which:

Figure 1 is a top plan view of the sharpening device in position for grinding the disc blades of a harrow;

Figure 2 is a sectional elevational view of the turntable taken along the line 2—2 of Figure 1;

Figure 3 is a side elevational view of the power means mounted in alignment with the driven disc blades;

Figure 4 is a detailed view of the split pulley mounted on the blade shaft for rotation therewith;

Figure 5 is a sectional view taken along the line 5—5 of Figure 4;

Figure 6 is a perspective view of a mounting bracket for interconnecting adjacent I-beams comprising part of the mounting frame, and

Figure 7 is a perspective view of the blade shaft supporting block mounted on an I-beam.

The illustrated embodiment of the invention comprises a supporting frame F consisting of multiple metal parts, which in the assembled relation forms a rigid, adjustable structure for the support of the operating elements. For this purpose, a pair of metal connectors C securely join a cross I-beam 10 with one end portion of a pair of laterally spaced parallel I-beams 11 and 12, disposed on the ground in the direction perpendicular to the first beam, and in a manner enabling adjustment of one beam relative to the others adjacent. The metal connector C may be a casting or a formed sheet metal stamping, and if the latter, the oppositely extending pairs of arms 14, 15 and 16 and 17 of a cross-shaped stamping 13 are folded upon themselves in op-

2

posed directions. For example, one pair of arms 16 and 17 folded upwardly, and the other pair 14 and 15 downwardly, forming horizontal but perpendicularly aligned grooves, each with a transverse central slot 18 and 18' between the arm ends, respectively, so that the groove portion slidably may engage the adjacent flanged portion of each I-beam. In this manner, the lower groove of the connector engages the upper flange of the longitudinally disposed beam and the upper groove slidably engages the lower flange of the cross beam. Each connector is stationarily positioned in the assembled relation by set screws 19, threadably engaging apertures 20 through each arm, enabling adjustment toward or away from the enclosed flanged section of each I-beam.

An upright block 21 of wood, metal or other rigid material is slidably mounted on each side beam 11 and 12, respectively, by means of a clamp 22 secured to the underside of the block, and for this purpose clamp 22 consists of a metallic strip having its ends 23 and 23' down-turned so as to provide a channel 24 having the contour of the flanged section of the I-beam to be disposed therein. Set screws 25 in the clamp, adjustable for engagement with the beam, militates against the relative shifting movement of the block from the desired position. The distance between the parallel side beams 11 and 12 is arranged so that the spaced journal boxes 26, supporting the freely rotatable shaft 27, may seat in the grooves 27' defined by the upright arms 28 of a metallic channel member 29, secured by screws 30 to the upper surface of each supporting block 21. Thus, the discs 31, in the grinding position, are supported away from the ground in a manner militating against their relative longitudinal movement, but enabling free rotational movement.

Rotational movement is imparted to the shaft 27 by power means P consisting of an electric motor 32 operatively joined with a reducer 33 through axially aligned flexible coupling means 34, all of which are adjustably mounted on a supporting plate 350 positioned on one inner end portion of a side beam as by clamping means previously described in connection with the supporting block 21. An endless belt 35 operatively joins a pulley 36 secured to the end portion of a rotatable shaft 37 extending from the reducer 33 with a split pulley 38 secured to the shaft 27. The split pulley, of standard construction, consists of a pair of substantially semi-circular peripherally grooved sections A and B, each having an integral central hub portion 39 grooved

so as to fit on the shaft 27. The semi-circular sections are mounted on the shaft 27 by means of a pair of bands 40 connected as by bolts and nuts 41, through registered apertures in diametrically disposed ears 42 extending from each band. Thus uniform rotational movement is imparted to the shaft 27 and the mounted disc blades 31 so that even grinding thereof is obtained from one position of adjustment, as hereinafter explained.

One other means, illustrated in Figure 3, for actuating the shaft 27 comprises the elements previously described, but instead, the motor 32' and reducer 33' are mounted in alignment with the shaft 27 so that chuck 360 positioned on the end of the reducer may operate releasably to engage the outer end portion of the shaft to impart rotational movement thereto. The plate or bed on which the motor 32' and reducer 33' are mounted, is suitably secured to a beam 350', one end portion of which is supported by a standard 351' and the other end of which is clamped to an I beam.

A grinding unit is mounted for sliding movement on the cross arm 10, different positions of the unit being illustrated by the solid and broken lines in Figure 1, and consists essentially of an electric motor actuating means 43 for driving a grinding wheel 44 secured to the end of an elongate shaft 45 intermediately supported by a bearing 46 and operatively connected to the spindle 47 of the motor through a flexible coupling 48. The above parts are assembled to comprise a unitary structure on a mounting plate 49 supported by a turntable T enabling free rotational movement of the grinding assembly. Force urging the grinding unit in one direction, when in the mounted position, is imparted thereto by means of a coil spring 50 having one end 51 secured intermediate of the mounting plate 49, the other end being anchored to a bracket 52 moveably secured to the cross beam 10 in spaced relation with the mounting plate 49.

As illustrated in Figure 1 of the drawings, the grinding assembly G is mounted on the cross beam 10 in a manner to direct the rotating grinding wheel 44 towards engagement with selected disc 31.

For the purpose of enabling free rotational movement of the grinding unit G, a turntable T is provided consisting of a block 53 having a central transverse groove 54 contiguous with a channel groove 55 having a contour similar to that of the upper portion of the I-beam 10 enabling sliding movement of the block relative thereto. Set screws 56, threadably engaging apertures 57 through the underside of block, are adapted to bear against the flanges of the I-beam when in the desired position of lateral adjustment, militating against subsequent relative movement thereof until such time as the screws are again retracted from engagement with the I-beam 10. A central pillar 58 integral with another upwardly extending pillar 59 of smaller diameter provides a shoulder 60 there-between on which seats one race of an antifriction roller bearing 61. The other race engages an internal shoulder formed by the side walls 62 and an annular ridge 63 of an inverted cup-shape member 64 disposed over and spaced from the concentric pillars. The cup-shaped member 64 is firmly positioned in the vertical plane relative to the supporting block by means of a flat head bolt 65 adapted loosely to fit through a central aperture 66 in the cup-shaped member and threadably to en-

gage a threaded aperture 67 in the upper pillar 59. A roller bearing 68 disposed between the underside of the flat head bolt and the upper surface of the cup-shaped member enables free relative rotational movement therebetween. In this manner the cup-shaped member 64 is firmly positioned and yet is rotatable independently of its support. Counter-sunk screws 69 disposed through the side walls 62 of the cup-shaped member threadably engage the mounting plate 49 which is apertured in a manner enabling the turntable T to be disposed therein.

In operation the side beams 11 and 12 first are disposed on the ground in a direction perpendicular to the axle 27 and in alignment with each journal box 26, and they are interconnected in that position by the superposed cross beam 10 by means of the connectors C previously described. The upright blocks 21 are then positioned on each side beam 11 and 12 and the shaft 27 raised so as to dispose the journal boxes in the channels 28 enabling the shaft 27 and mounted discs 31 to be rotated freely by one of the power means described. Thereafter the turntable T with attached mounting plate 49 may be shifted transversely on the cross beam 10 to the predetermined position of adjustment to provide the desired angular relationship between the grinding wheel 44 and the discs 31. The independent actuating means enables uniform rotational movement of the disc and grinding wheel respectively, the coil spring 50 urging the members towards engagement with each other with equal force so that uniform grinding is obtained throughout the periphery of each blade 31. It is manifest that the grinding unit G may be shifted laterally on the beam 10, thus to engage the front or rear of each blade as desired.

From the above description, it is manifest that I have produced a simple device for sharpening the disc blades of a harrow or the like, in a manner which does not necessitate disconnection thereof from the traction means and from a direction that does not conflict with the frame work of the farm machinery. The device combines relatively few readily available elements that are easily assembled into a unitary sturdy structure particularly adapted for the purposes desired. In addition, flexibility and adjustment of the grinding forces and grinding angle may be made without effort or the expenditure of considerable time.

Thus I have produced a simple, portable but compact unit for grinding blades of various elements and particularly the disc blades of a harrow without the need of transporting the more cumbersome machines to a central processing location.

It is to be understood that numerous other changes may be made in the details and construction arrangement and operation without departing from the spirit of the invention especially as defined in the appended claims.

What I claim is:

1. A disc grinding device comprising a disc carrying shaft, a pair of spaced parallel supporting frame members disposed substantially at right angles to the disc carrying shaft, a cross arm connecting said members and adjustable longitudinally thereof, a block releasably mounted on each of said members for supporting the disc carrying shaft, a grinding wheel, a turntable mounting said wheel and translatorily shiftable transversely on said cross arm, means for securing said turntable against translatory shifting

movement, spring means connecting the turntable and cross arm for urging said grinding wheel into engagement with a disc, and individual driving means for the disc carrying shaft.

2. A disc grinding device as claimed in claim 1, in which the supporting frame members and cross arm comprise I beams, and brackets connecting said cross arm to each frame member, said brackets being adapted slidingly to fit a flanged portion of each adjacent beam respectively, and set screws in said brackets engageable with said beams for locking same in the assembled position.

3. A disc grinding device as claimed in claim 1, in which the blocks comprise rigid pillars having a frame member engaging bracket on one end and a channel on the other mounting the disc carrying shaft, and set screw means for releasably securing said bracket in position.

4. A disc grinding device as claimed in claim 1, in which the turntable comprises a block having a groove adapted slidingly to engage said cross arm, means for locking said block in the desired position of sliding adjustment, integral hub sections of large and small diameter respec-

10
15

tively, an inverted cup-shaped member disposed over said hub sections, anti-friction means between the cup member and hub sections, a bolt disposed through an aperture in said cup member and threadably engaging said hub sections, and anti-friction means disposed between the head of said bolt and said cup-shaped member.
